UNITED STATES PATENT OFFICE

WILLIAM R. EDMISTER, OF COLUMBUS, OHIO, ASSIGNOR TO THE CAPITAL LIFT AND MFG. CO., OF COLUMBUS, OHIO, A CORPORATION OF OHIO

HOISTING MECHANISM

Application filed September 20, 1927. Serial No. 220,810.

This invention relates broadly to improvements in hoisting or lifting mechanisms and with regard to the more specific features thereof, has particular application to hoisting devices of the kind used in connection with cellar and basement doorways for effecting the elevation of refuse or other materials from the floor of a cellar or basement to a higher or street level.

An outstanding object of the present invention resides in providing swinging cellar doors of the type used in opening or closing sidewalk cellar shafts with a foldable frame structure upon which is carried a hoisting mechanism, whereby when said doors assume an open position the frame structure may be extended and operatively erected for the purpose of facilitating the hoisting of materials through the shaft from lower to higher levels, and whereby when the doors are closed the frame structure may be collapsed to assume a folded position suspended from the under side of the doors in order that the mechanism will be out of the way and free from the floor surface of the cellar or basement immediately beneath the doors and at the bottom of the shaft.

Hoisting devices of this character heretofore in use have been formed to include supporting frames mounted directly upon the floor of the shaft and independently of the door structure generally. As a result a double installation expense has been involved, first, the mounting and cutting of the door structure at the top of the shaft and second the mounting and setting of the hoisting mechanism on and in the shaft and its floor. Further, engineering calculations have been necessary to adapt such frame structures to shafts of varying height and as a result of this considerable expense is involved in such installation and many errors due to the lack of properly supplied engineering data.

In accordance with the present invention the hoisting mechanism is mounted directly on the swinging doors and their associated supporting frame and therefore the installation expense is limited merely to the proper

setting of the swinging doors and their frame, which is present in all cases whether the hoisting mechanism is provided or not. Again, the present invention permits the door and hoisting mechanism to be supplied as a unit and renders the mechanism independent of the depth of the shaft or opening in which the mechanism is mounted.

With these and other objects in view, as will appear as the description proceeds, the invention consists in the novel features of construction, combinations of elements and arrangements of parts hereinafter to be more fully described and pointed out in the appended claims.

In the accompanying drawings:

Figure 1 is a view in side elevation of the improved hoisting mechanism comprising the present invention illustrating the same mounted in connection with the swinging doors of a cellar shaft way, the doors being disclosed in vertical section,

Figure 2 is a similar view disclosing the frame structure of the hoisting mechanism in a partly folded position,

Figure 3 is a similar view disclosing the frame structure in its fully folded position and the associated doors in their closed position,

Figure 4 is a view in front elevation of the hoisting drum,

Figure 5 is a top plan view thereof,

Figure 6 is a side elevation of said hoisting drum looking toward the reverse side thereof as regards the showing in Figure 1,

Figure 7 is a fragmentary end elevation of the upper end of the hoisting mechanism.

Referring more particularly to the drawings the numeral 1 designates the hoisting mechanism comprising the present invention in its entirety. This mechanism is mounted in connection with the ordinary swinging doors employed for covering the upper end of a cellar shaft way. These doors are indicated by the numeral 2—2 and have their outer edges provided with brackets 3 which rotatably engage transversely extending shafts 4 mounted in connection with a structural steel frame 5. This frame

is embedded as usual in the concrete or other materials used at the upper end of the shaft way 6, the upper edges of the frame 5 terminating flush with the pavement street level 7. One of the doors 2 has its outer edge provided with an angle iron 8, which provides a rest for the reception of the meeting edge of the other door. It will be understood that when the doors are closed, as indicated in Figure 3, the same also lie flush with the street level 7. When the doors are opened the same swing through an angle of slightly more than 90 degrees so that said doors by engaging with the frame 5 will tend automatically to maintain themselves in open positions as is customary in structures of this class.

The doors 2 are united by means of chains 9 having their end links connected with eyes 10 fixed to the doors, the chains 9 serving to equalize the stresses and strains on the doors when the latter are open. When opened the doors are further braced by means of pivoted braces 11 and 12, the former having its upper end pivotally connected as at 13 to the door on which the hoisting mechanism is mounted, and the lower part thereof slides through a strap guide 14, and has its lower end connected with a cable 15, the latter being trained over pulleys 16 mounted in connection with the frame 5, the depending portion of the cable having fastened thereto a weight structure 17, which serves as a counterbalance to facilitate the raising and lowering of the door section on which the hoisting mechanism is mounted, permitting said door sections to be readily raised and lowered by hand. A pin 18 passes transversely through aligned openings provided in the strap guide 14 and is employed to lock the door sections on which the hoisting mechanism is mounted in its open position. The pin 18 is readily removable, however, to allow free movement on the part of said door sections. The ends of the guides 14 are provided with rollers to facilitate the sliding movement of the brace 11. The brace 12 is pivoted as at 19 to the door section which is unweighted, and has its lower end provided with a recess which receives a fixed stud 20 provided on the frame 5, and which serves to positively maintain the unweighted door section in its open position and to permit of the functioning of the chains 9.

The hoisting mechanism comprises a frame formed to include a stanchion 21, which is riveted or otherwise rigidly secured to one of the door sections 2, and rotatably mounted upon the outer or upper end of the stanchion 21 is a drum frame 22, which when the door structure is open, is capable of turning about a substantially vertical axis. Pivotally connected to the upper or outer part of the drum frame 22 is the lower section 23 of a foldable mast 24. The section 23 includes a

laterally bent lower end which, when the mast is elevated, rests upon an angle bar 25 fastened to the upper portion of the drum frame. Adjacent to this laterally bent portion of the frame section 23 is a pivoted link 26, having a recess formed in its outer or free end. This recess engages with the horizontal leg of the angle 25 to hold the section 23 of the mast in the elevated position shown in Figure 1 and to resist the weight applied thereto when hoisting is being done.

Pivotally connected with the upper or outer end of the section 23 as at 27 is the upper or outer section 27 of the mast. This section includes a pair of bars which are bent to substantially ball form, as shown in Figure 1. The adjacent bars of the sections 23 and 27 are provided with registering openings for the reception of a removable pin 28. The openings in which the pin 28 is received are arranged on opposite sides of the pivotal connection between the mast sections in order that the pin may function for the purpose of locking the sections against movement in both their open and closed positions, see Figures 1 and 3. The pin 28 is attached to a chain 29 which prevents the same from becoming accidentally lost or misplaced.

The drum frame 22 comprises a rotatable shaft 30, which is journaled in the side plate of the frame. This shaft is revolved manually by means of a crank 31, although it is in the scope of the present invention to employ motor driven means for revolving the shaft 30 if desired. The shaft 30 is provided with a pinion 32, which meshes with a gear 33 arranged on a drum shaft 34, the latter being journaled in the hoist frame immediately below the shaft 30. Rotatable with the shaft 34 is a drum 35, around which is wrapped and secured a hoisting cable 36. This cable passes upwardly and is trained about a guide sheave 37 slidably mounted on the shaft 30. From the sheave 37 the cable is trained upwardly and is passed around a guide pulley 38 carried by the upper section 27 of the foldable mast. From the pulley 38 the cable is trained around a sheave wheel 39 located at the extreme outer end of the section 27, and from this point the cable drops downwardly and has its outer or lower end provided with a hook 40, which is adapted to engage a lifting bail 41 provided upon an ash container 42. By this construction it will be observed that when the crank 31 is rotated motion will be imparted to the drum 35 so as to wind the cable 36 thereabout, thus shortening the effective length of said cable and permitting of the raising of the container 42 to a desired horizontal level. The shaft 30 has its end opposite to the crank 31 provided with a ratchet wheel 43, with which engages a pivoted dog 44, by means of which the drum may be locked in any given position of rotation. In

the lowering of the container, however, the dog 44 is raised to clear the teeth of the wheel 43 so as to permit the container to drop under the action of gravity. The descent of the 5 container, however, is governed by means of a friction strap 45, which fastens around a friction wheel 46 fixed on the drum shaft 34.

In view of the foregoing it will be seen that the present invention provides a closure 10 structure for basement or cellar shafts having unitarily connected therewith a hoisting mechanism which may be readily extended, upon the opening of the closure, to assume an operative position and collapsed or folded 15 when the closure assumes a shut position so as to be out of the way and to require but a minimum of storage space. The construction has the advantage of being readily adaptable to cellar or basement shafts of any 20 height, and may be installed unitarily and simultaneously with the associated door structure so as to minimize installation cost. The device possesses considerable mechanical 25 strength and is fully capable of withstand-
ing the stresses and strains incident to the service which it is intended to perform.

What is claimed is:

1. In mechanism of the character described, the combination with a sidewalk 30 frame, a door pivotally mounted in said frame and arranged for vertical swinging movement through an arc in excess of 90°, an angularly formed stanchion fastened at one end to the under side of said door and 35 so disposed that the free upper portion of said stanchion is vertical when said door is fully opened, a hoisting mechanism carried by said stanchion, a brace pivotally connected at one end to said door, means for 40 locking said brace to said frame to positively retain said door in its opened position, and means cooperating with the other end of said brace to counterbalance the weight of the mechanism carried by said door.

45 2. In mechanism of the character described, the combination with a sidewalk door structure including a frame provided with a pair of doors, downwardly extending brackets carried by each of said doors near 50 their outer ends, pivotal connections between said brackets and said frame so as to permit each of said doors when fully opened to move through an arc in excess of 90° and to extend upwardly and outwardly, an angularly 55 formed stanchion fastened at one end to the under side of one of said doors and so disposed that the free portion of said stanchion is vertical and positioned to one side of the opening covered by said door structure when 60 said door is fully opened, hoisting mechanism carried by said stanchion, a brace pivotally connected at one end to the under side of said door carrying said stanchion and slidably received in said frame, means for 65 locking said brace to said frame to positively

secure said door when in an open position against movement, and means operating against the other end of said brace to counterbalance the weight of the mechanism carried by said door.

In testimony whereof I affix my signature.

WILLIAM R. EDMISTER.
